DESIGN FOR A COAT

Bertha Weinstein and Jack Pine, New York, N. Y.

Application January 17, 1938, Serial No. 74,350

Term of patent 3½ years

To all whom it may concern:

Be it known that we, Bertha Weinstein and Jack Pine, citizens of the United States and residents of Manhattan, in the city, county, and State of New York, have invented a new, original, and ornamental Design for a Coat, of which the following is a specification, reference being had to the accompanying drawing, forming part thereof.

Fig. 1 is a front view of a coat showing our new design.

Fig. 2 is a rear view thereof.

The characteristic feature of our design resides in the specific three-tiered collar, each tier being piped in a contrasting color, in combination with the specific coat as shown.

We claim:

The ornamental design for a coat, substantially as shown and described.

BERTHA WEINSTEIN.
JACK PINE.
